UNITED STATES PATENT OFFICE.

THEODORE HAVILAND, OF AMBAZAC, FRANCE.

DESIGN FOR A COVERED DISH.

SPECIFICATION forming part of Design No. 24,995, dated December 24, 1895.

Application filed September 26, 1895. Serial No. 563,805. Term of patent 7 years.

To all whom it may concern:

Be it known that I, THEODORE HAVILAND, a citizen of the United States, residing at Am-
bazaac, in the Department of Haute-Vienne,
5 Republic of France, have invented and pro-
duced a new and original Design for Dishes;
and I do hereby declare the following to be a
full, clear, and exact description of the same,
reference being had to the accompanying
drawings, forming a part thereof.

The principal feature of my design consists
of a low covered dish divided into panels.
Around the body of the dish passes a chain or
twisted vine-like decoration. The same deco-
ration marks the periphery of the cover and
the base of the dish.

Figure 1 represents a side view of the dish;
Fig. 2, a face view of the cover.

In Figs. 1 and 2, the letters A A represent
the chain or twisted vine-like decoration; B B,
the markings of the panels; C C, the decora-
tions of the handles; D, the acanthus-like and
grape-vine leaf ornamentation.

Around the body of the dish, Fig. 1, the
chain or twisted vine-like decoration passes, 25
terminating near the handles in acanthus-like
ornamentations joined with a resemblance of
grape-vine leaves D D. This same decora-
tion marks the periphery of the cover, Fig. 2.
The ornamentations of the handles C C are 30
marked with fruit and leaves, the representa-
tions of the fruit being placed on the top of
the handles as well as upon the body of the
dish where the handles join it.

What I claim is—

The design for a dish substantially as shown
and described.

In testimony whereof I have affixed my sig-
nature in presence of two witnesses.

THEODORE HAVILAND.

Witnesses:

ST. CLAIR MCKELWAY,
ARMAND GOUTERON.
